Fig. 2.

The diagram illustrates a vacuum tube power supply circuit. On the left, an 'R.F. INPUT' terminal is connected to the filament winding of a vacuum tube. The filament is heated by a 'CATHODE HEATING SUPPLY' (indicated by two '00000' symbols) and a resistor R . The filament circuit also includes a diode D and a capacitor C . The filament is connected to the cathode of the tube. The anode of the tube is connected to the 'R.F. OUTPUT' terminal. A magnetic field coil surrounds the tube, with its ends labeled M and N . The coil is connected to a power source TL and includes a diode D and a capacitor C . The magnetic field coil is wound around the tube, with its ends M and N connected to the power source TL . The tube itself is labeled with various points: A' , A'' , C' , E , E'' , K , and A . The filament is labeled F .

Application February 21, 1946, Serial No. 649,342

9 Claims. (Cl. 315—39)

1

This invention relates to an electron discharge device and circuits therefor, and particularly to magnetron amplifiers.

In the oscillating space charge inside a magnetron oscillator, the forces which determine the oscillation, or which are essential for oscillation, are relatively small at a location close to the cathode but relatively large at a location near the anode. In practicing the present invention, I contemplate making use of this phenomenon by introducing forces close to the cathode by means of power derived from an external source, in order to control the frequency or amplitude of oscillation, and thus obtain a large ratio of output power to input power.

The present invention overcomes a characteristic of the magnetron which is very undesirable from the standpoint of the user, and which is present in conventional magnetrons. In operating standard types of magnetron oscillators for continuous wave operation, it is necessary to raise the anode-to-cathode potential to some value near the cut-off potential (where all electron emission strikes the anode without returning to the cathode) in order to initiate oscillations. After oscillations have started, this potential must be reduced to a much lower value in order to obtain good efficiency of conversion of direct current power to alternating current power. By means of the present invention, I can control the magnetron to produce oscillations without the necessity for raising the anode-to-cathode potential.

In accordance with the invention, I provide two or more control wires or rods near the cathode of the magnetron and apply alternating current potential between them in order to control the production of much larger alternating current potentials at the anode. This anode may take the form of two substantially semi-cylindrical segments or four arcuate-shaped segments symmetrically positioned around the cathode; or may take the form of a cavity resonator. The control wires or rods extend parallel to the cathode and are preferably positioned close to the cathode compared to the location of the anode. A magnetic field is utilized providing flux lines parallel to the axis of the cathode but transverse to the cathode-to-anode path.

A more detailed description of the invention follows in conjunction with a drawing, wherein:

Figs. 1 to 5 are cross-sections of five different magnetron embodiments of the present invention and circuits therefor, and

Fig. 4a is a section of the magnetron of Fig. 4 along the lines a—a, and also shows the oscillating field and electron paths within the magnetron.

Referring to Fig. 1, there is shown a magnetron of the split anode type having an evacu-

2

ated envelope E containing therein an indirectly heated linear cathode K and a pair of semi-cylindrical anode segments A, A, symmetrically positioned around the cathode. A coil or other suitable means for producing a magnetic field parallel to the cathode but transversely to the cathode-to-anode path is shown diagrammatically in dot and dash lines designated F. A pair of control wires or rods C, C are positioned physically parallel to each other and to the cathode but on opposite sides of and close to the cathode K. These control rods, wires or electrodes are used to start and control operation of the magnetron. Connected to these control rods C, C is a parallel tuned circuit M to which is magnetically coupled the alternating current from a source of radio frequency IN. This source may be a source of continuous waves of constant frequency and amplitude, or a source of radio frequency signals. Connected to the anodes A, A is a parallel tuned output circuit N, and magnetically coupled to this output circuit N is a transmission line TL which passes the radio frequency energy abstracted from the magnetron to a suitable load shown as an antenna.

The cathode K is supplied with heating current over a pair of leads extending to an iron core transformer T. The control rods C, C are maintained at a moderate positive potential relative to the cathode by means of a lead P, one end of which is connected to the electrical mid-point of the input tuned circuit M and the other end of which is connected to a tap on a potentiometer R. Potentiometer R is connected between ground and a positive terminal of a source of unidirectional potential. It should be noted that this positive terminal is also connected to the electrical mid-point of the tuned output circuit N via lead S, thus supplying anode polarizing potential to the anode segments A, A. Radio frequency by-pass condensers D, D connect the leads P and S to ground, as shown.

In the operation of the system of Fig. 1, the two control rods or electrodes C, C are fed in opposite phase by the input alternating current from source IN. It should be noted, therefore, that the potential of one control rod C is varied relative to the other control rod C and that both of these control rods vary in potential relative to the cathode and anode. Because the control rods are relatively close to the cathode, the radio frequency input power IN can be made to be relatively small compared to the output power which is derived from the output parallel tuned circuit N. These control rods C, C control the output frequency or power of the magnetron by means of the relatively small electro-magnetic energy introduced close to the cathode. Output tuned circuit N may be resonant to the same frequency as input tuned circuit M or in har-

monic relation to the input frequency supplied to the control rods.

The system of the invention is primarily adapted for use in magnetron amplifiers wherein continuous waves may be generated and synchronized by input power supplied to the control rods C, C although it should be understood that, if desired, the input power may be supplied in pulses, in which case the output power would also be in pulses of radio frequency energy.

In the operation of the invention, the control rods C, C may be at a moderate positive potential relative to the cathode, or at a potential anywhere in a range from a moderately negative potential to a moderately positive potential with respect to the cathode, and in comparison with the anode direct current potential, depending upon the detailed dimensions of the magnetron elements, particularly the cathode diameter. The anode direct current potential is usually comparatively high in value compared to the values of the other potentials applied to the electrodes of the magnetron.

Fig. 2 shows how the invention can be applied to a magnetron having two pairs of arcuate-shaped anode segments A', A' and A'', A'', in which oppositely located segments are directly connected together and at the same radio frequency potential, while adjacent anode segments are at instantaneously opposite radio frequency potentials. In Fig. 2 the control wires or rods C', C' are positioned close to and physically parallel to the cathode but located between the cathode and anode segments having opposite instantaneous radio frequency potentials. Thus, one control electrode C is between the cathode K and an anode segment A', while the other control electrode C' is connected between the cathode K and another anode segment A''.

The two control rods or wires C', C' of Fig. 2 are fed by tuned input circuit M in opposite phase, in the manner similar to the way the control rods of Fig. 1 are fed, although the control rods of Fig. 2 are not on opposite sides of the cathode. It should be noted that the control rods are adjacent anode segments of opposite phase in the particular embodiment of Fig. 2. The circuit elements of Fig. 2 which are the same as those of Fig. 1 have been given the same reference characters.

Fig. 3 is a modification of Fig. 2, wherein four control rods are utilized and symmetrically positioned around the cathode. These control rods are designated C, C and C', C'. The rods C', C'' are connected together and the rods C, C are connected together. One pair of rods C, C is connected to one side of the tuned input circuit M, while the other pair of rods C', C' is connected to the other terminal of the tuned input circuit M. All four control rods are positioned relatively close to and physically parallel to the cathode.

Fig. 4 shows the invention applied to a magnetron whose anode is in the form of a cylindrical cavity resonator W. The cathode K is shown along the axis of the magnetron, while the two control rods or electrodes C, C are shown on opposite sides of the cathode K. It should be noted that opposite end walls of the cavity resonator W have apertures which are sealed by glass windows G. One of the glass windows G is utilized to withdraw output energy from the magnetron, which can be radiated therethrough or carried away in a suitable wave-guide X, shown connected to the cavity resonator W. Obviously, if desired,

the wave guide X can be dispensed with, and energy abstracted from the magnetron through a suitable probe or coupling loop inserted into the cavity resonator. The probe or coupling loop can be connected to a suitable output transmission line extending to an antenna or other utilization circuit. The cavity resonator W of Fig. 4 acts as the equivalent of a double anode in a double anode magnetron. The axial magnetic field has not been shown in Fig. 4 in the interest of simplicity of the drawing. The electric field of Fig. 4 is at right angles to the cathode and at right angles to the drawing; that is, in a direction away from the eyes of the observer. The cavity resonator is resonant at right angles to the illustration of Fig. 4, or across the diametrical dimension from left to right, or vice versa, of the showing of Fig. 4a. Fig. 4a illustrates a section of Fig. 4 along the lines a—a, and shows the oscillating electric field and the electron paths. The plus and minus signs on the control rods C, C designate the opposite instantaneous input potentials on these electrodes applied by the alternating current input source IN.

Fig. 5 illustrates the invention applied to a multi-resonant cavity type of magnetron having a plurality of inwardly projecting targets on the anode structure Z. This cavity resonator structure Z acts as the anode and is sometimes called a scalloped type of anode. Input power is supplied by a source of radio frequency input current IN which is inductively coupled to lead P extending from potentiometer R to the control rods C, C. Lead P is tuned by means of condenser D' which is slidably along the lengths of lead P and cathode lead P'. This condenser is a short-circuit or a path of extremely low impedance for energy of the input frequency.

It should be noted that in this construction both control rods C, C are directly connected together and fed cophasally relative to the cathode. The control rods C, C are on opposite sides of the cathode K and in electrically parallel relation to each other. The scalloped anode structure Z is grounded, as shown. A field coil F provides an electromagnetic field parallel to the cathode and transversely to the anode-to-cathode path. Output from the magnetron is taken from a loop L which passes out through a hole in the anode structure Z and connects to the inner conductor of a coaxial line TL'. A glass seal J seals off this hole in the cavity resonator. The frequency of the input source IN and the frequency of the output energy may be the same or harmonically related to each other.

The general construction of the magnetron, except for the use of the control rods C, C may be generally of the type described in my United States Patent 2,217,745, granted October 15, 1940.

Although the present invention has been described as using two and four control rods symmetrically positioned around the cathode, it should be understood that six or more control rods can also be employed in practicing the invention along the same principle outlined above without departing from the spirit and scope of the invention.

What is claimed is:

1. A magnetron comprising a cathode, an anode structure having a plurality of spaced target portions surrounding said cathode, and a pair of spaced control wires parallel to and insulated from each other and said cathode, but spaced closer to said cathode than to said anode structure, means for producing a magnetic field acting

transversely to the anode-to-cathode path, said control wires being arranged on opposite sides of said cathode, each of said control wires being arranged between said cathode and one of said target portions, and leads connected to said control wires for supplying alternating current input power thereto.

2. A magnetron amplifier comprising a cathode, an anode structure having a plurality of spaced target portions surrounding said cathode, a pair of spaced control wires parallel to and insulated from each other and said cathode but spaced closer to said cathode than to said anode structure, and each located on a straight line extending from said cathode to a point substantially centrally located relative to the ends of one of said target portions, means for producing a magnetic field acting transversely to the cathode-to-anode path, a tuned circuit connected to said control wires to supply opposite instantaneous potentials thereto, a source of input radio frequency energy coupled to said tuned circuit, and means coupled to said anode structure for deriving from said anode structure radio frequency energy of larger power than said source of input power and of a frequency the same as or harmonically related to said input energy.

3. A magnetron comprising an evacuated envelope, a cathode within said envelope and along the axis thereof, an anode including a pair of arcuate shaped anode segments around said cathode, a pair of spaced control wires parallel to and insulated from each other and said cathode but spaced closer to said cathode than to said anode, one of said wires being positioned between said cathode and the central portion of one anode segment while the other wire is positioned between said cathode and the central portion of the other anode segment, a parallel tuned circuit connected to said control wires to supply opposite instantaneous potentials thereto, a source of radio frequency input power coupled to said tuned circuit, and means for producing a magnetic field acting transversely to the cathode-to-anode path.

4. A magnetron comprising an evacuated envelope, a cathode within said envelope and along the axis thereof, an anode including a pair of arcuate shaped anode segments around said cathode, a pair of spaced control wires parallel to and insulated from each other and said cathode but spaced closer to said cathode than to said anode, one of said wires being positioned between said cathode and the central portion of one anode segment while the other wire is positioned between said cathode and the central portion of the other anode segment, a parallel tuned circuit connected to said control wires to supply opposite instantaneous potentials thereto, said anode segments and control wires being located in adjacent quadrants of a circle, a source of radio frequency input power coupled to said tuned circuit, and means for producing a magnetic field acting transversely to the cathode-to-anode path.

5. A magnetron comprising an evacuated envelope, a cathode within said envelope and along the axis thereof, an anode including a pair of arcuate shaped anode segments around said cathode, a pair of spaced control wires parallel to and insulated from each other and said cathode but spaced closer to said cathode than to said anode, one of said wires being positioned between said cathode and the central portion of one anode segment while the other wire is positioned between said cathode and the central portion of the other anode segment, a parallel tuned circuit

connected to said control wires to supply opposite instantaneous potentials thereto, said anode segments and control wires being arranged symmetrically on opposite sides of said cathode, a source of radio frequency input power coupled to said tuned circuit, and means for producing a magnetic field acting transversely to the cathode-to-anode path.

6. A magnetron amplifier comprising a cathode, an anode structure surrounding said cathode and having a plurality of spaced targets, a pair of spaced control wires parallel to and insulated from each other and said cathode but spaced closer to said cathode than to said anode, said wires being located on opposite sides of said cathode, each of said control wires being arranged between said cathode and one of said targets, means for producing a magnetic field acting transversely to the cathode-to-anode path, and means coupled to said control wires for supplying radio frequency power to said control wires in cophasal relation.

7. A magnetron comprising a cathode, an anode structure having a plurality of spaced target portions surrounding said cathode, a pair of spaced control wires parallel to and insulated from each other and said cathode, but spaced closer to said cathode than to said anode structure, means for producing a magnetic field acting transversely to the anode-to-cathode path, each of said control wires being between said cathode and one of said target portions, and leads connected to said control wires for supplying alternating current input power thereto.

8. A magnetron comprising a cathode, an anode structure having a plurality of spaced target portions surrounding said cathode, a pair of spaced control wires parallel to and insulated from each other and said cathode, each of said control wires being between said cathode and one of said target portions, means for producing a magnetic field acting transversely to the anode-to-cathode path, a tuned circuit connected to said control wires to supply opposite instantaneous potentials thereto, and a source of input alternating current power coupled to said tuned circuit.

9. A magnetron comprising a cathode, a hollow cylindrical anode structure coaxially surrounding said cathode and including at least one pair of spaced anode segments of substantial circumferential length, a pair of control wires parallel to and insulated from each other and said cathode but spaced closer to said cathode than to said anode structure, each of said control wires being between said cathode and the mid-point of one of said anode segments, means for producing a magnetic field acting transversely to the anode-to-cathode path, and leads connected to said control wires for supplying control potentials thereto.
